HOUSEHOLD JACK

Edward Schultz, Chicago, Ill.

Application August 2, 1954, Serial No. 31,715

Term of patent 14 years

(Cl. D41—1)

Fig. 1 is a front perspective view of a household jack embodying my new design; and

Fig. 2 is a rear perspective view thereof.

The essential features of my design reside in the portions shown in full lines.

I claim:

The ornamental design for a household jack, as shown and described.
